HAND HOIST

Humphrey F. Parker, Kenmore, and Erford E. Robins, Tonawanda, N. Y., assignors to Columbus McKinnon Chain Corporation, Tonawanda, N. Y., a corporation of New York

Application December 16, 1944, Serial No. 568,420

7 Claims. (Cl. 254—169)

1

The principal object of our invention has been to provide a hand hoist which shall be light and compact, sturdy in design, and of relatively few parts, whereby it may be inexpensively manufactured.

Another object has been to provide a two-part hand chain guide, one portion thereof being formed by an end wall of the frame or housing and the other portion being detachably secured thereto, whereby one portion may be readily detached to make the hand chain easily accessible for assembling or disassembling.

Another object has been to provide a hoist having a Weston brake located adjacent the inside hub of the hand wheel which latter part closely fits into the frame portion of the hand chain guide, whereby the brake will be enclosed within a chamber and thus protected against the accumulation of dust and dirt.

A further object has been to provide a hoist with a single gear reduction and with a load-lift wheel of relatively few teeth.

Moreover, the load chain guide of our device is supported by one of the side walls of the frame and may be made of two coacting parts held together and to the wall by suitable fastening means.

Furthermore, our hoist may be provided with aligning inserts for the load chain guide. These inserts are carried by one of the end walls, and thereby not only facilitate the machine work on the frame but provide means for aligning the guide, as well as convenient assembly and disassembly.

The above objects and advantages have been accomplished by the device shown in the accompanying drawings of which:

Fig. 1 is an external view of our hoist with the gear cover removed;

Fig. 2 is a side elevation of the completed hoist;

Fig. 3 is an enlarged sectional plan view of the hoist and is taken on the line III—III of Fig. 1;

Fig. 4 is a reduced fragmentary sectional view taken on line IV—IV of Fig. 3; and

Fig. 5 is a fragmentary front view of the hoist with portions broken away for clearness of illustration.

Our hoist comprises a frame or housing 10 having an outer wall 11 and spaced end walls 12 and 13. An intermediate wall 14 extends from the end walls 12 and 13 and serves to provide with the other walls a shaft chamber 15. The

2

end wall 13 extends only to the boundaries of the outer wall 11, whereas the end wall 12 extends beyond the confines of the outer wall in an extension 16. This extension together with the wall 12 forms the inner guide 20 of the hand chain guide 21. The outer portion 22 of this guide is in the form of a separable part substantially co-extensive with the extension 16 and a portion of the wall 12. This portion of the guide is formed with upper spacing sleeves 23 and with a lower spacing sleeve 24. A lateral wall 25 is also provided on this portion of the guide and it connects the upper spacing sleeves 23 and serves to enclose the upper portion of the chain guide. This portion of the guide is secured to the other portion of the guide and to the frame by means of bolts 26 which extend through the sleeves 23 and 24 and into the frame. The portion 22 of the chain guide is preferably formed with an opening 30 for the passage of the hand wheel 31 which is engaged by the hand chain 32 in usual manner, such chain being endless and extending down below the hoist and within reach of the operator.

Our hoist is provided with but a single gear reduction and therefore has a gear pinion 33 mounted upon and formed integrally with a hand wheel shaft 34. This shaft is mounted in suitable anti-friction bearings 35 and 36 mounted in suitable openings formed in the walls 12 and 13, respectively. These bearings are preferably of the grease retaining type so that they will resist the passage of oil and grease through them. The hand wheel shaft extends beyond the wall 12 and upon it is mounted the usual Weston brake 40. As is customary, this brake comprises a friction hub 41 non-rotatably carried by the wheel shaft 34 and having a flange 42 and a sleeve shaped hub 43. The hub is provided with the usual screw threads for engagement with screw threads provided in the hub 44 of the hand wheel 31. The hub 44 is preferably of the same diameter as the flange 42 and between it and the flange there is rotatably mounted the ratchet wheel 45 of the brake. The usual friction washer 46 is arranged at each side of the ratchet for producing the necessary friction and causing the ratchet wheel and hand wheel to be frictionally locked to the friction hub under certain conditions of operation. By reference to Fig. 5, it will be seen that a ratchet pawl 50 is pivotally mounted upon a pawl stud 51 and held in contact with the teeth 52 of the ratchet wheel.

by means of a spring 53, which is preferably wrapped about the hub (not shown) of the pawl. This spring has one end 54 bearing on top of the pawl and the other end engaged with a stop pin 55. The pawl stud is rigidly fixed in the wall 12 or the extension 16 thereof.

The frame 10 is formed in one of its faces with a recess 37 and the inner flange 38 of the hand wheel is disposed within this recess. Clearance space 39 between the periphery of the wheel flange and the recess is reduced to a minimum so that a substantially closed chamber 37 is provided within which the Weston brake is mounted thus protecting it against the accumulation of dust and dirt.

The pinion 33 extends beyond the wall 13 and meshes with a load gear 56. The pinion and load gear are mounted within a gear chamber 60 formed by a gear cover 61 which is secured to the frame 10 adjacent the wall 13. The load gear is non-rotatably supported upon a load wheel shaft 62, which shaft extends inwardly to a point adjacent the wall 12. This shaft is mounted in ball bearings 63 and 64 carried respectively, by the walls 12 and 13. The load-lift wheel 65 of our device is preferably provided with three teeth 66 formed integrally with the shaft 62. The load-lift wheel is mounted in a wheel chamber 70 formed between the side wall 12 and 13 and a portion of the outer wall 11 together with the inner wall 14. Mounted within this chamber is a load chain guide 71 of our hoist. This guide may be of two-part construction having an outer member 72 and an inner member 73. The member 72 is formed with a hub portion 74 and with a flange portion 75 of substantially the same size as the portion 73, whereby a recess is provided for the reception of the outer sides of the chain links lying in planes at right angles to the axis of the wall. The inner and outer members 72 and 73 of the load chain guide are secured in place by means of bolts 76. In order to facilitate the machining of the surfaces against which the chain guide is to bear, we have provided inserts 80 for each of the bolts 76, one of which being shown in section in Fig. 3 and both of which being showed in dotted lines in Fig. 1. These inserts are machined so that their end faces when in position will hold the guide in proper alignment, and they are so proportioned in relation to the apertures in the end wall 13 with which they are engaged that they are frictionally held in place by a pressing fit.

A stripper 81 is provided on our hoist and is located beneath the load-lift wheel 65. This stripper is held in place by means of screws 82 passing through the wall 12 and extension 16 thereof.

The loose end 83 of the load chain 84 is mounted in a recess 87 formed in the housing 10 and is held therein by means of a pin 85. This pin is preferably formed on the end of one of the cover screws 86 and is disposed in a suitable hole formed in the housing. The ball bearings 36 and 64 are preferably held in place by a bearing retainer 90 which, as shown in Fig. 1, extends over a portion of these bearings, the end being concave as shown in Fig. 1 to conform substantially to the shape of the bearings.

The casing is provided with a top wall 91 above which is arranged a hook abutment 92 with which the stem 93 of the upper hook 94 is engaged. This abutment is in spaced relation with the top wall so as to provide a lateral channel 96 for the

accommodation of the nut 95 carried by the lower end of the hook stem 93.

What is claimed is:

1. A hoist comprising a frame having end walls and connecting side walls forming a load-lift wheel chamber, a load-lift wheel disposed in said wheel chamber and having a load-lift shaft supported in bearings carried by said end walls, a load chain engaging said load-lift wheel, a load chain guide mounted in said wheel chamber, inserts fixedly carried by one of said end walls and projecting into said wheel chamber, and means passing through said inserts and engaging said chain guide for securing the same in registration with the load wheel.
2. A housing comprising a frame having end walls and connecting side walls forming a load-lift wheel chamber and an operating shaft chamber, a load-lift wheel disposed in said wheel chamber and having a load-lift shaft supported in suitable bearings carried by said end walls, an operating shaft passing through said shaft chamber and supported in suitable bearings in said end walls, gear means connecting said load-lift wheel shaft with said operating shaft, a hand chain wheel carried by said operating shaft, a multi-part hand chain guide arranged about said wheel, one part of said guide being integral with said frame, and the other part thereof being detachably secured to the first part, a load chain engaging said load-lift wheel, a two-part load chain guide disposed in said wheel chamber, sleeve inserts carried by one of said end walls and having their inner faces in abutting relation to said load chain guide, and means for securing said last mentioned guide to the inserts.
3. A housing comprising a frame having end walls and connecting top and side walls forming a load-lift wheel chamber, a load-lift wheel disposed in said wheel chamber and having a load-lift shaft supported in suitable bearings carried by said end walls, an operating shaft supported in suitable bearings in said end walls, gear means connecting said load-lift wheel shaft with said operating shaft, a suspension hook abutment disposed between and integrally cast with said end walls, said abutment being in spaced relation with said top wall outside of said wheel chamber thereby forming a lateral recess, a suspension hook carried by said abutment, retaining means carried at the lower end of said hook and disposed in said lateral recess, a hand chain wheel carried by said operating shaft, and an annular multi-part hand chain guide, one part of said guide being integral with said frame and formed with an annular recess for the reception of the inner flange only of said hand wheel, and the other part of said guide being detachably secured to the first part and formed with an upper wall extending across the chain groove of said hand chain wheel, whereby the joint between said guide parts is so positioned that when said detachable part is removed the hand chain will be accessible for removal.
4. A hoist comprising a frame having end walls and connecting side walls, one of said end walls having an extension, an operating shaft mounted in suitable bearings in said end walls, a hand chain wheel carried by said operating shaft and having an inner flange and an outer flange, a Weston brake mounted upon said shaft and located between said hand wheel and the end wall having the extension, an annular multi-part hand chain guide having a fixed part and a detachable part, said fixed part being formed by said end

wall and its extension, said end wall and said extension being formed with an annular recess for the close-fitting reception of the inner flange only of said hand wheel, whereby the brake will be substantially enclosed, said chain guide also having a separable part, and means for detachably securing said guide parts together.

5. A hoist comprising a frame, a load-lift wheel carried by said frame, a hand chain wheel rotatably carried by said frame and having an inner flange and an outer flange, gear means connecting said load-lift wheel and said hand wheel, and an annular multi-part hand chain guide having a frame part and a detachable part, the joint between said chain guide parts lying in a plane substantially parallel with the flanges of said hand wheel, said frame part being integral with said frame and formed with an annular recess for the reception of the inner flange only of said hand wheel, said detachable part being secured to said frame part and formed with a laterally extending upper wall for engagement with said frame part to form therewith a house over the upper portion of said hand wheel, whereby the joint between said guide parts is so positioned that when said detachable part is removed the hand chain will be accessible for removal.

6. A hoist comprising a frame, a load-lift wheel carried by said frame, a hand chain wheel rotatably carried by said frame and having an inner flange and an outer flange, gear means connecting said load-lift wheel with said hand wheel, and an annular multi-part hand chain guide having a frame part and a detachable part, the joint between said chain guide parts lying in a plane substantially parallel with the flanges of said hand wheel, said frame part being integral with said frame and formed with an annular recess for the reception of the inner flange only of said hand wheel, said detachable part being secured to said frame part and formed with an inwardly and laterally extending wall for engagement with said frame part, said wall cooperating with said

frame part to house the upper portion of said hand wheel, and a spacing sleeve carried at the lower portion of said detachable part for engagement with the frame part of said guide.

5 7. A hoist comprising a frame, said frame having end walls, side walls connected to said end walls, and a top wall connected to said end and said side walls, thereby forming a load-lift wheel chamber closed at its upper end, a load-lift wheel disposed in said wheel chamber and having a load-lift shaft supported in bearings carried by said end walls, a load chain engaging said load-lift wheel, a load chain guide mounted in said wheel chamber and located between said top wall and said load-lift wheel, said guide comprising an inner member and an outer member, said outer member having a hub portion and a flange portion, said hub portion abutting said inner member, whereby a chain receiving groove is formed therebetween, and fastening means passing through said inner member and the adjacent wall and threaded into said hub for holding said guide in alignment with said load chain.
